ERASER RETAINING CAP AND CLIP

Serafin Garcia Lopez, New York, N. Y.

Application January 11, 1950, Serial No. 137,943

4 Claims. (Cl. 120—7.5)

1

This invention relates generally to writing utensils and more particularly to novel structure for combining a mechanical or an automatic pencil with a ball point fountain pen and a cap having a pencil eraser associated therewith.

Another object of this invention is to provide a novel cover or cap for the fountain pen portion of the combined writing utensil having a removable, or replaceable, eraser carried by a reversible holder at the outer end of the cap, and in which the cap is so constructed as to limit the movement of the eraser into the cap and also to resiliently hold the eraser in position on the cap.

Still another object of the invention is to provide a supporting clip for the cap or closure of the ball point pen, in which the clip is so constructed as to prevent inadvertent disengagement of the eraser from the cap on which it is removably disposed.

With these objects, and others which will appear as the description proceeds, in view, my invention resides in the combination and arrangement of parts, and the details of construction, set forth in the description and illustrated in the drawing and then more particularly defined in the appended claims.

In the drawing:

Figure 1 is a longitudinal view of a combined pen and pencil constructed according to an embodiment of my invention and substantially broken away to show the internal structure thereof.

Figure 2 is a transverse section taken on the line 2—2 of Figure 1.

Figure 3 is a fragmentary longitudinal section of a modified device.

Figure 4 is a transverse section taken on the line 4—4 of Figure 3.

Figure 5 is a fragmentary detailed view, partly broken away, and on an enlarged scale, of a cap or closure constructed according to another embodiment of this invention.

Figure 6 is a view similar to that of Figure 5 with the erasing element carried by the cap in exposed position.

Figure 7 is a detail view, on an enlarged scale, of an eraser holder constructed according to another embodiment of this invention.

Figure 8 is a transverse sectional view taken on the line 8—8 of Figure 5.

Figure 9 is a detail view, on an enlarged scale, of a fountain pen reservoir receptacle constructed according to another embodiment of my invention.

Figure 10 is a side elevation of an erasing element and a retainer, or holder, therefor of a conventional type.

Figure 11 is a fragmentary side elevational view of a supporting clip for the cap of a fountain pen, of the form illustrated by Figure 1, and

Figure 12 is a top view of the clip illustrated in Figure 11.

Referring to the drawing, and initially to Fig-

2

ures 1, 2, 11, and 12 thereof, I have disclosed an embodiment of a combined pen and pencil constructed according to this invention. The combined pen and pencil, generally indicated by the numeral 10, includes generally a mechanical pencil 11 connected in end to end relationship to a fountain pen 12 of the ball point type.

The mechanical pencil section 11 of the device includes a tapered elongated hollow cylindrical body 13 open at the opposite ends thereof. A pencil lead advancing and retracting mechanism 14 is disposed within the hollow body 13, and extends outwardly through the smaller end thereof. The lead advancing and retracting mechanism 14 includes a tapered, or conical, end piece 15, which is fared into the smaller end of the tapered body 13. The larger end of the body 13 is internally threaded as at 16, and is also provided with a reduced diameter annular shoulder 17. A cylindrical member 18 tightly engages within the hollow body 13 and is closed at one end as at 19. As seen in Figure 1, the cylindrical member 18 opens towards the larger end of the body 13.

The fountain pen section 12 of the combined pen and pencil 10 includes a tapered elongated body 20 having a reduced diameter threaded portion 21 extending from the larger end thereof. The larger end of the tapered body 20 has a diameter equal to the diameter of the seat 17 formed at the larger end of the body 13, and the reduced diameter threaded portion 21 engages the internal threads 16 of the body 13 for securing the pencil section to the pen section of the device. An elongated tubular reservoir 22 extends from the reduced diameter portion 21 of the fountain pen body 20, and projects into the cylindrical member 18. The tubular reservoir 22 is formed with radially extending openings 23 adjacent the end thereof. A passageway 24 extends through the wall of the body 13 and the cylindrical member 18 for venting the tubular reservoir 22 to the atmosphere. A ball point of conventional design 25 extends from the reduced diameter end of the body 20 of the pen section.

A cap member, generally indicated by the numeral 26, is provided for enclosing the ball point fountain pen 12, when the latter is not in use. The cap 26 includes an elongated tapered hollow open ended body 27. The large end of the body 27 is dimensioned for frictional engagement over the large end of the body 20 and onto the seat 17 at the large end of the body 13. This frictional engagement maintains the cap 26 in position covering the pen section 12 of the device. A supporting clip 28 is mounted upon the body 27 of the cap, and includes a resilient arm 29, extending parallel to the longitudinal axis of the body 27, and an annular portion 30 formed integral with one end of the arm and engaging over the smaller end of the tapered body 27. The inner edge of the annular portion 30 is crimped as at 31 for securing the annular portion, and therefore the supporting clip 28 to the cap. As seen

in Figure 1, crimping of the edge of the annular portion 30 as at 31 forms an inwardly directed annular rim or shoulder 32 on the inner surface of the body 27 adjacent the smaller end of the latter. An erasing element 33, including a cylindrical holder 34, and an abrading element 35 extending therefrom, is mounted within the smaller end of the body 27. As seen in Figure 1, the annular rim 32 engages the edge of the holder 34, and thereby limits the movement of the erasing element 33 into the body 27. The holder 34 of the erasing element is indented at 36 for retaining the abrading element 35 within the holder.

In Figures 3 and 4 I have illustrated a modification of the cylindrical member 13 mounted within the body 13 of the pen section 11. The cylindrical member 13a, closed at one end by the end wall 19a, is formed with circumferentially spaced apart longitudinally extending inwardly offset channels 37, which open towards the large end of the body 13a. As shown in Figure 4, a plurality of additional writing lead 38 may be stored in each of the channels 37, and are accessible when the body 20a of the pen section is removed from the body 12a of the pencil section.

In Figures 5, 6, and 8, I have illustrated a modification of the cap 26b, in which the body 27b is formed with the annular inwardly directed rib 32b adjacent the smaller end of the body. In this modification, semi-circular resilient tabs 39 are struck inwardly from the body 27b, between the annular groove forming an internal rib 32b and the adjacent end of the body. The resilient tab 39 engages against the side of the holder 34b of the erasing element 33b for retaining the erasing element in its position in the smaller end of the body 27b. In Figure 5, the erasing element is shown in an inverted position, with the abrading member 35b extending into the body 27b, in a position of non-use. In Figure 6, the erasing element has been disposed in the body 27b in operative position, with the abrading element 35b extending outwardly of the small end of the body 27b.

In Figure 7, I have illustrated a modification 33c of the erasing element. In this modification, the cylindrical holder 34c is provided with longitudinally extending circumferentially spaced apart outwardly struck resilient ribs 40. The ribs 40 resiliently engage the inner surface of the smaller end of the body of the cap. The resilient engagement of the ribs 40 with the cap, not shown, will retain the erasing element 33c in its selected position on the smaller end of the cap.

In Figure 9, I have disclosed a further modification 18d of the cylindrical member fitted within the body 13 for receiving the reservoir 22 of the fountain pen. The cylindrical member 18d is open at each of its opposite ends, and a cup-shaped member 41 is provided for closing the end of the cylindrical member normally closed by the end wall 19, as shown in Figure 1. The cup-shaped member 41 is formed with a diameter substantially equal to that of the cylindrical member 18d, and is formed with the spaced apart slots 42 opening through the edge 43 thereof. The slots 42 form a plurality of resilient tongues 44, which may be sprung inwardly and extended into one end of the cylindrical member 18d. Since the diameter of the cup-shaped member 41 is substantially equal to the outer diameter of the cylindrical member 18d, it is apparent that portions 45 of the slots 42 will be exposed beyond the adjacent edge of the cylindrical member 18d.

when the cup-shaped member is urged to the limit of its movement into the member 18d. The exposed portions 45 of the slots will thereby provide means for venting the interior of the cylindrical member 18d within which the reservoir 22 is normally disposed.

Finally, in Figure 10 I have illustrated a conventional type of replaceable erasing element 33e. The erasing element 33e includes a holder 34e having bent gripping arms 46 which engage the abrading element 35e. This conventional type of erasing element may be substituted for the erasing element 33 shown engaged with the cap 26 in Figure 1.

Having thus described various modifications of the elements of my combined pen and pencil, what I claim as new and desire to secure by Letters Patent is:

1. A cap for a combined pen and pencil comprising an elongated, open ended hollow body, a clip for said body including an annular portion engaging about one end of said body, a crimped inner edge on said annular portion securing said clip to said body and forming an inwardly directed annular rib on the latter adjacent to and spaced from said one end, and an erasing element in said one end of said body engaging said rib for limiting the movement of said erasing element into said body and for yieldably retaining said erasing element within said body.

2. A cap according to claim 1 wherein said erasing element includes a cylindrical holder formed with circumferentially spaced apart longitudinally extending outwardly directed ribs resiliently engageable with the inner surface of said body and at their ends abutting against said annular rib for limiting the inward movement of the erasing element, and an abrading member secured in said holder and extending from one end thereof.

3. A cap for a combined pen and pencil comprising an elongated open ended hollow body, an inwardly directed annular rib formed in said hollow body adjacent to and spaced from one end of the latter, an erasing element receivable in said one end of the body, means on said erasing element engageable axially with one side of said annular rib for limiting the movement of said element into said body and engageable radially with the internal surface of said hollow body for yieldably retaining said element within said body, and a clip having an annular portion engaging about said one end of the body, said annular rib being formed by a crimped inner edge of said annular portion of the clip securing said clip to the body.

4. A cap according to claim 3; wherein said limiting and retaining means includes longitudinal ridges on said erasing element for frictional engagement with the inside surface of said body and for end engagement with said annular rim.
